UNITED STATES PATENT OFFICE.

CHARLES E. BRADSHAW, OF WATERBURY CONNECTICUT.

BUCKLE.

Application filed May 18, 1921. Serial No. 470,564.

To all whom it may concern:

Be it known that I, CHARLES E. BRADSHAW, a citizen of the United States, residing at Waterbury, in the county of New Haven and State of Connecticut, have invented a new and useful Improvement in Buckles; and I do hereby declare the following, when taken in connection with the accompanying drawings, and the characters 10 of reference marked thereon, to be a full, clear, and exact description of the same, and which said drawings constitute part of this application, and represent in—

Fig. 1 a rear view of a buckle constructed 15 in accordance with this invention and shown as applied to a piece of webbing.

Fig. 2 a side view of the same.

Fig. 3 a detached view of the loop member.

20 Fig. 4 a detached view of a modified form of loop.

Fig. 5 a side view of the same, showing it in connection with a piece of webbing.

Fig. 6 a side partly in section view of a 25 buckle having a loop, as shown in Fig. 4, with a clip by which the web is connected thereto.

Fig. 7 a view of a loop, as shown in Fig. 4, connected to a piece of webbing by means 30 of a staple.

Fig. 8 a sectional view on the line 8—8 of Fig. 7.

Fig. 9 a view of a loop, as shown in Fig. 4, connected to a piece of webbing by means 35 of headed rivets or studs.

Fig. 10 a sectional view on the line 10—10 of Fig. 9.

This invention relates to improvement in buckles, and particularly to buckles comprising a wire loop-like frame formed from a 40 single piece of wire, the ends of which are bent inward to form pintles upon which a lever is mounted. The object of this invention is to so construct the loop as to facilitate webbing and reduce the amount of webbing generally necessary, and the invention 45 consists in the constructions as hereinafter described and particularly recited in the claims.

50 In carrying out my invention, I employ a wire loop 15, formed from a single piece, with inwardly turned ends 16 upon which is mounted a lever 17 having the usual grip-

edge 18. The central portion of the loop is flattened so as to reduce the thickness of the 55 wire, and it is formed with upwardly projecting bends 19 and 20 on opposite sides of the center, the adjacent portions of the bends being connected by a U-shaped bridge 21, which stands directly in the rear of the projections 19 and 20 and between which the end 22 of a piece of webbing may be clamped and thus secured to the loop without stitching, and thus reducing the amount of web generally necessary. As in buckles of this 60 type, the web extends from the loop downward through some supporting means not shown and upward between the loop and the lever, between which it is gripped. Instead of employing the bridge 21, this may be 65 omitted, as shown in Fig. 4 of the drawings, so as to produce two upwardly extending projections 23, which, being flattened, will readily pass through slots formed for them in the webbing, as indicated in Fig. 5 of the 70 drawings; or, instead of having the projections extend through the webbing, the webbing may be secured to the projections by a U-shaped clip 24, as shown in Fig. 6 of the drawings; or, instead of using a clip, a staple 25 may be passed through the webbing 75 and between the bends in the projection and the ends folded over, as indicated in Figs. 7 and 8 of the drawings; or, instead of a staple, two headed rivets 26 may be passed 80 through the webbing between the bends in the loop and upset on the lower face of the webbing, as indicated in Figs. 9 and 10 of the drawings. In every case, the central portion of the loop is flattened, so as to reduce 85 the thickness and form a surface against which the running portion of the web is clamped by the lever and in each instance the web is secured to the loop without stitching, thus simplifying the time required to 90 attach the web to the buckle and reducing the amount of web usually necessary.

I claim:

1. A buckle comprising a wire loop and a lever pivotally connected with the ends 100 thereof, the loop flattened between its ends and formed with upwardly-extending bends forming flat bearing surfaces with which the lever coacts.

2. A buckle comprising a wire loop and a 105 lever pivotally connected therewith, the cen-

tral portion of the loop formed with an upwardly-projecting U-shaped bridge, and with two upwardly-turned bends at the ends of the bridge, between which bridge and bends the web is adapted to be gripped, and with which bridge the lever co-acts.

In testimony whereof, I have signed this

specification in the presence of two subscribing witnesses.

CHAS. E. BRADSHAW.
